UNITED STATES PATENT OFFICE.

MARK A. SMITH AND CHARLES F. YAEGER, OF EVANSVILLE, INDIANA;
SAID SMITH ASSIGNOR TO SAID YAEGER.

BROOM.

SPECIFICATION forming part of Letters Patent No. 355,223, dated December 28, 1886.

Application filed December 29, 1885. Serial No. 187,056. (No model.)

To all whom it may concern:

Be it known that we, MARK A. SMITH and CHARLES F. YAEGER, citizens of the United States, residing at Evansville, in the county 5 of Vanderburg and State of Indiana, have invented certain new and useful Improvements in Brooms; and we do declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 Figure 1 of the drawings is a representation of this invention, and shows a cross-section through the upper portion of a broom and the two metallic bands. Fig. 2 is an edge view of one band inclosing the broom-straw, and Fig. 20 3 is an edge view of the other band before they are joined in the broom. Fig. 4 is a front view of a portion of a broom.

This invention has relation to the manufacture of brooms; and it consists in the construction 25 and novel arrangement of devices, all as hereinafter set forth, and pointed out in the appended claims.

In the accompanying drawings, the letter A designates a metallic band angularly bent 30 at B B, and of sufficient size to receive the quantity of broom-straw needed to make one half, A', of the broom. This band A is formed from a single sheet-metal strap, C, which is first bent up at B B, to form the arms D D'. 35 The prepared broom-straw is then laid upon the portion E, between the arms D D', but does not occupy the entire space between said arms. The arm D is then bent inwardly and downwardly upon the butt-ends of the broom-straw, and extends nearly over to the arm D'. The arm D' is next bent inwardly upon the broom-straw and upon the arm D, and extends nearly across the broom-straw. The portion 40 of the broom thus formed is then placed in a forming-machine, and the depression or concave bend F is formed midway between its ends, at which time this half of the broom is ready to be bent to receive the other half of

the broom, which differs slightly in its construction from the half just described. 50

The second half, I, of the broom is formed as follows: A shorter sheet-metal strap, L, is used in its construction, and is first bent up at M M' to form the arms N N'. The broom-straw is laid upon the portion O of said strap, 55 between the arms N N', and extends from arm to arm of said strap L. The arms N N' are then bent inwardly, so as to compress and hold the broom-straw, and this portion or half of the broom is next placed in the machine 60 and compressed to form the depression or half-socket P. The lower end of the handle Q is then laid in the half-socket P and secured in place by a nail, R. The portion or half I is then laid upon the half A' of the broom, the 65 handle Q resting in the half-socket of said portion or half A'. The projecting ends S S' of the portion A' are next bent inwardly over the portion or half I of the broom, and are compressed thereon, so as to firmly unite the 70 two sections or halves together, and thus complete the broom. By constructing a broom after this method we are enabled to produce a strong, cheap, and durable broom.

Having described this invention, what we 75 claim, and desire to secure by Letters Patent, is—

1. A broom-section consisting of a vertical half of the broom-straw bound by a metal band compressed thereon, and provided with a depression midway between the ends of said compressed band, substantially as specified. 80

2. A broom-section consisting of a vertical half of the broom-straw bound by a compressed metal band having its end projecting at the 85 sides of the broom-section, substantially as specified.

3. A broom-section consisting of a vertical half of the broom-straw bound by a compressed metal band having projecting ends and a central half socket or depression therein, substantially as specified. 90

4. The combination, with a broom-section bound by a metal band having a middle depression or concavity, of the broom-handle 95 and a broom-section bound by a metal band

having a middle depression and inwardly-bent clamping ends, substantially as specified.

5. A broom formed in two separately-bound sections, one of which is provided with extensions adapted to overlap the opposite section in uniting the same, substantially as specified.

6. A broom having its straw formed in two bound sections, depressed at opposite points to receive a stick, and united, substantially as specified.

In testimony whereof we affix our signatures in presence of two witnesses.

MARK A. SMITH.
CHARLES F. YAEGER.
